(57) **CLAIM**

We claim the ornamental design for a wearable foot garment, as shown and described.

DESCRIPTION

FIG. 1 is a perspective medial view of our new design as it appears when worn on a left foot of a wearer.

FIG. 2 is a bottom view thereof.

FIG. 3 is a top view thereof; and,

FIG. 4 is a perspective lateral view thereof.

The dot-dot-dash lines, showing the wearer's heel and ankle, are included to illustrate the environment of the design as worn and form no part of the claimed design.

The dot-dash lines are boundary lines that show that the claimed design extends to but does not include the boundary line.

The evenly dashed broken lines inside the claim boundary depict a knit pattern and form no part of the claim.

The evenly dashed lines outside the claim boundary are for the purpose of depicting portions of a wearable foot garment and form no part of the claim.
